UNITED STATES PATENT OFFICE.

JAMES MARTIN HOWLETT, OF DENVER, COLORADO.

AUTOMATIC BOTTLE-STOPPER.

1,217,093.

Specification of Letters Patent.

Patented Feb. 20, 1917.

Application filed May 14, 1915. Serial No. 27,966.

To all whom it may concern:

Be it known that I, JAMES MARTIN HOWLETT, a citizen of the United States, residing at the city and county of Denver and State of Colorado, have invented certain new and useful Improvements in Automatic Bottle-Stoppers; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in bottle stoppers, my object being to provide a stopper adapted for use in a bottle whose contents are to be removed in relatively small quantities. This bottle is well adapted for use as a bar bottle, where liquors are dispensed by the glass. It is also well adapted for use as a bottle for holding medicine of any kind, soda fountain syrups, table sauces, and toilet preparations, as hair tonics, cologne, etc.

My improved stopper is used to take the place of the ordinary cork after the latter has been removed. For instance, the bar-keeper or other user removes the regular cork from a bottle and substitutes my improved stopper, which forms a proper closure and at the same time, permits the removal of any portion of the contents of the bottle, and as soon as the latter is returned to the upright position, the stopper automatically seats itself and forms a proper closure.

An important feature of my improved stopper consists in its adjustability, whereby the contents may be poured with relative freedom from the bottle or may be dispensed slowly or by drops, as may be desired. Hence, it will be found exceedingly convenient where medicine is to be dispensed or removed from the bottle in drops.

Having briefly outlined my improved construction, I will proceed to describe the same in detail, reference being made to the accompanying drawing, in which is illustrated an embodiment thereof. In this drawing,—

Figure 1 is a vertical section taken through a bottle equipped with my improved stopper, the lower part of the bottle being broken away.

Fig. 2 is a detail view of the stopper, showing a cork sleeve applied.

Fig. 3 is a view of the device, the stopper being shown in the inverted position, whereby its valve or closure member is unseated.

Fig. 4 is a view showing the bottle tilted to unseat the stopper feature to permit the escape of the bottle's contents.

Fig. 5 is a view showing the stopper adjusted to completely close the bottle at all times for the purpose of preventing the escape of its contents, should it be tipped over or accidentally thrown to such a position as to unseat the valve or closure member when adjusted as in the other views.

Fig. 6 is a sectional view in detail, of the adjustable sleeve applied to the stem of the stopper, shown on a larger scale.

Fig. 7 is a section taken on the line 7—7, Fig. 2, viewed in the direction of the arrow.

The same reference characters indicate the same parts in all the views.

Let the numeral 5 designate my improved stopper, considered in its entirety, the same being composed of a shell 6, a valve piece 7, a stem 8, a sleeve 9, a lock nut 10, and a guide member 12 connected with the shell 6 by arms 13. The shell of the stopper is surrounded by a sleeve 14 composed of cork or other suitable or similar material. The body portion 15 of the shell is cylindrical in shape and in its lower extremity the arms 13 are located. These arms form the support for the guide member 12, which is perforated to receive the stem 8. The upper portion of the shell is outwardly flared or enlarged to form a seat 16 for the valve or closure piece 7 which is secured to the outer extremity of the stem. Beyond the seat 16 the shell is provided with a circumferential flange 18 which overlaps the upper extremity 19 of the neck of an ordinary bottle 20, thus limiting the insertion of the stopper.

The stem 8 of the stopper extends inwardly beyond the shell 6, and its inner extremity is threaded as shown at 21. To this threaded portion of the stem, the sleeve 9 is applied, the sleeve being interiorly threaded, as shown at 22, for the purpose. To the inner extremity of the stem, beyond the adjustable sleeve, a lock nut 10 may be applied, whereby the sleeve is secured in the adjusted position.

By referring to Fig. 1 of the drawing, it will be understood that when the sleeve 9 is adjusted as shown in this view, the space 113 between the upper extremity of the sleeve and the lower extremity of the guide 12

indicates the opening movement of the valve or closure piece 7 when the bottle is inverted or tilted to unseat the valve (see Figs. 3 and 4). If it is desired to open the bottle 5 to allow a still greater flow of liquid, the sleeve 9 may be adjusted to increase the space 24 between the adjustable sleeve 9 and the guide sleeve 12 of the device. Furthermore, it is evident that if it is desired 10 to restrict the flow, the sleeve 9 may be moved toward the inner extremity of the guide sleeve 12, to permit as little opening movement of the valve piece as desired, or none, if necessary, the last named construction being shown in Fig. 5.

From the foregoing description, the use and operation of my improved bottle stopper will be readily understood. Assuming that the regular cork or stopper has been 20 removed from a bottle whose contents are to be intermittently dispensed, my improved stopper is substituted therefor. It will be understood that the cork sleeve 14 may be of any desired size or thickness. In other 25 words, the body of my improved stopper comprising the shell 6 may be of uniform size and still be adapted for use with bottles whose neck openings are of varying sizes, by employing cork sleeves of varying 30 thickness. It is also evident that the shell 6 may be made of any desired size.

Attention is called to the fact that the valve piece is preferably disk-shaped, its 35 exposed portion when in the seated position being convex, while its lower or inner portion is curved to fit the seat 16 of the shell. This exterior curvature of the valve piece has a tendency to deflect any liquid or other material that might accidentally 40 come in contact with the valve when in the seated position, thus preventing any possibility of such liquid or material entering the bottle.

Furthermore, the valve piece is interiorly 45 recessed as shown at 25, whereby when the valve is unseated and the liquid is being removed from the bottle, it will enter this recess or pocket, which will prevent the liquid from being deflected or scattered beyond the desired area as it is poured from 50 the bottle. After entering this recess, the liquid will flow downwardly either in drops

or in a continuous stream, as may be desired, and will thus be under the perfect control of the user of the bottle. If the valve piece 55 had its inner surface convexly curved, there would be a tendency to cause the liquid to scatter or be thrown a considerable distance as it escaped from the bottle. This recess 25 completely overcomes any tendency of 60 this character.

The shell 6 is provided where its cylindrical portion 15 joins the part 16, with an offset or shoulder 26, which forms a positive stop for the adjacent extremity of the 65 cork sleeve 14 and prevents any tendency to split the cork, as might be the case in the absence of this offset or shoulder. In other words, if the exterior surface of the part 16 were beveled or curved directly from the 70 adjacent extremity of the cylindrical part 15, there would be a tendency, as the cork sleeve is crowded into place, for it to follow the incline or curve, which of course, would spread and split the sleeve. The shoulder 75 26 overcomes this difficulty.

Having thus described my invention, what I claim is,—

A stopper comprising a cylindrical shell adapted to enter the neck of a bottle, a 80 sleeve composed of yieldable material surrounding said shell and adapted to fit the bottle neck, the upper portion of said shell being formed with an outwardly curved portion terminating in a circumferential 85 flange adapted to engage the upper extremity of the bottle neck, said portion providing a valve seat, a centrally located guide member supported near the inner end of said shell, a valve adapted to coöperate with 90 said valve seat, a valve stem therefor extending through said guide member inwardly beyond said shell, said valve stem carrying thereon an adjustable sleeve adapted to coöperate with said guide member to 95 regulate the distance which the valve will move off its seat when the bottle is tilted or placed in an inverted position.

In testimony whereof I affix my signature in presence of two witnesses.

JAMES MARTIN HOWLETT.
